UNITED STATES PATENT OFFICE.

CLARENCE BOLES, OF HUGOTON, KANSAS.

LEAF-SPRING.

1,327,016.

Specification of Letters Patent.

Patented Jan. 6, 1920.

Application filed February 10, 1917, Serial No. 147,830. Renewed September 19, 1919. Serial No. 325,039.

To all whom it may concern:

Be it known that I, CLARENCE BOLES, a citizen of the United States, residing at Hugoton, in the county of Stevens and State of Kansas, have invented certain new and useful Improvements in Leaf-Springs, of which the following is a specification.

This invention relates to new and useful improvements in vehicle springs and more particularly to a leaf spring for automobiles and the primary object of the invention is to provide such a spring as will create a resisting and rebounding action substantially equivalent to shock absorbers, whereby the latter may be eliminated from the vehicle.

A further object of the invention resides in providing a master leaf which is designed to form a cap over the other leaves of the spring and which is designed with a roller bearing at its end to receive in frictional engagement therewith the lower or longer leaf of the spring.

A still further object resides in providing depending lugs or the like on the cap spring which are positioned to contact with the side edges of the shorter leaves adjacent the ends thereof.

Still another object of the invention resides in providing a device which is simple and durable in construction, inexpensive to manufacture and one which will be very efficient and useful in operation.

With these and other objects in view my invention consists in the novel features of construction, combination and arrangement of parts, as will be hereinafter referred to and more particularly pointed out in the specification and claims.

40 In the accompanying drawing, forming a part of this application:—

Figure 1 is a side elevation of a spring constructed in accordance with my invention;

45 Fig. 2 is a longitudinal section therethrough; and

Fig. 3 is a transverse section through the same as seen on the line 3—3 of Fig. 2.

In describing the invention, I shall refer 50 to the drawing in which similar reference characters designate corresponding parts throughout the several views and in which 1 designates an upper or cap leaf spring, the ends of which have integrally or otherwise 55 secured thereto the clips or bracket-like sections 2 in which are provided friction rollers

3. Guided between these rollers in the clips 2 and extending beyond the latter is the lower and longer leaf 4 of my improved spring and arranged between the cap leaf 1 60 and the lower leaf 4 are a plurality of shorter leaves 5 which are graduated in length, as usual in connection with a vehicle spring of this type. The leaves 1, 4 and 5 are secured at their centers by means of a 65 center bolt or other securing member 6 and are otherwise not secured together in any respect whatsoever. The cap leaf 1, however, is provided at regular intervals along the side edges thereof with integral depending lugs 7, the same being arranged in pairs and designed to contact with the side edges of the leaves 5 adjacent the ends of the latter. Thus each leaf 5 is guided between four lugs 7 carried by the cap leaf 1. 75

By constructing this spring as hereinabove described and shown in the drawing, a resisting and rebounding action is had which is substantially equivalent to shock absorbers on a vehicle, and thus an automobile 80 equipped with springs such as the one herein described and shown, would eliminate the necessity for using such shock absorbers. Moreover, by securing the springs together at the centers thereof and by providing the 85 guides on the cap leaf for the intermediate leaf, great flexibility is had whereby to afford the resisting and rebounding action and at the same time eliminates the necessity of other securing means between the leaves. 90

From the foregoing description of the construction of my improved device, the manner of applying the same to use and the operation thereof will be readily understood and it will be seen that I have provided a 95 simple, inexpensive and efficient means for carrying out the objects of the invention.

While I have particularly described the elements best adapted to perform the functions set forth, it is obvious that various 100 changes in the form, proportion and in the minor details of construction, may be resorted to, without departing from the spirit or sacrificing any of the principles of the invention.

Having thus described my invention, what I claim and desire to secure by Letters Patent, is:—

1. In a spring of the class described, a cap leaf having a pair of rollers at one end, 110 a lower leaf slidably and frictionally disposed between said rollers, a plurality of

leaves between said cap and lower leaves, and means for securing said leaves together centrally.

2. In a spring of the class described, a cap leaf having a pair of rollers at each of its ends, a lower leaf slidably and frictionally disposed between said rollers, a plurality of leaves between said cap and lower leaves; means for securing said leaves together centrally, and means depending from said cap leaf for guiding and retaining the intermediate leaves in position.

3. In a spring of the class described, a cap leaf having a pair of frictional rollers at each of its ends, a lower leaf slidably disposed between the aforesaid rollers, a plu-

rality of shorter and graduating leaves disposed between said cap and lower leaves, means for securing said leaves together centrally, and a plurality of integral lugs 20 formed on and depending from said cap leaf to contact with the side edges of the shorter leaves, whereby to guide and retain the latter in position during the actions of the spring.

In testimony whereof I affix my signature in the presence of two witnesses.

CLARENCE BOLES.
